UNITED STATES PATENT OFFICE.

HARRY JONES, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,202,529.

Specification of Letters Patent. Patented Oct. 24, 1916.

Application filed April 28, 1916. Serial No. 94,090.

To all whom it may concern:

Be it known that I, HARRY JONES, a citizen of the United States, and a resident of Suffern, in the county of Rockland and State of New York, have made and invented certain new and useful Improvements in Brake-Shoes, of which the following is a specification.

My invention relates to brake shoes, and particularly to that type wherein the serviceable life and wear-resisting properties of the shoe are increased and lengthened by the presence of localized inserts of hard steel, the body of the shoe being reinforced throughout by the presence of openwork ductile metal. This type of shoe, as so constructed, involves several molding operations, and considerable labor in its manufacture, and in addition, the localized inserts of hard steel oftentimes become highly heated in service and the wearing properties of such inserts or sections impaired or destroyed.

It is therefore an object of the present invention to provide a brake shoe having one or more inserts composed of hard wear-resisting steel and openwork ductile metal, the hard steel and ductile metal being joined together in a unitary structure, and preferably in the form of a netting, extending throughout substantially the entire body of the shoe. The ductile metal portion of the insert reinforces and ties together the body of the shoe, and the uniform and widely distributed character of the hard wear-resisting steel, prevents the excessive heating of the shoe at any one point or locality, and provides for the even, uniform and slow wear thereof. By forming the insert of hard wear-resisting steel and of ductile metal, and combining the two in a unitary structure, the requisite frictional and wear-resisting properties are obtained, and a shoe is provided which may be economically and easily manufactured, involving but little labor and requiring but one molding operation for its production.

A further object is to provide a brake shoe insert composed of superposed layers of openwork or expanded metal, held together in a unitary mass by the presence of a coating of hard wear-resisting steel, the hardness of the wear-resisting steel being increased by the chill resulting from depositing it upon the cold ductile metal when in a highly heated condition.

Other objects and advantages will further appear.

The preferred embodiment of my invention is disclosed in the accompanying drawings, wherein:

Figure 1 is a view in top plan of a brake shoe embodying the characteristic features of my invention, portions of the shoe being broken away and represented in section; Fig. 2 is a fragmental view in perspective of the foregoing; Fig. 3 is a view in side elevation, and partially in section, of my improved brake shoe; Fig. 4 is a view in end section, of an insert composed of two superposed layers of expanded ductile metal, upon and around which the hard wear-resisting steel is deposited; Fig. 5 is a view in top plan of an insert with portions of the hard steel coating removed from the ductile metal netting.

Referring specifically to the several views, the insert is preferably composed of a bundle of superposed layers of openwork or expanded metal 10, preferably formed of ductile or malleable steel. A coating of hard wear-resisting steel 11 is formed upon the openwork metal and ties and binds the several layers thereof together, so that the insert is in the form of a unitary structure, as shown in Figs. 2 and 4, and may be handled and arranged within a brake shoe mold without difficulty, and without the usual assembling and wiring operations necessary to maintain localized inserts and superposed layers of expanded metal in position. The coating of hard wear-resisting steel is preferably formed upon the bundle of openwork metal, by dipping the latter into a crucible of highly heated steel, but the insert may consist of one or more layers of expanded metal separately coated with hard steel, as shown in Fig. 5. The depositing of the highly heated, hard steel upon the cool netting of ductile metal, imparts a chill to the hard steel, and accordingly adds materially to the hardness and the wear-resisting properties thereof.

The exact number of layers of expanded metal 10 may be varied, the insert disclosed in Figs. 2 and 3 being formed of four such layers, the insert disclosed in Fig. 4 being composed of two layers, and the insert illustrated in Fig. 5 consisting of but a single layer. The amount of hard wear-resisting steel deposited upon the strands of

the ductile netting may also be varied, by varying the temperature of the hard crucible steel in which the netting of ductile metal is immersed.

5. The insert is positioned within the brake shoe cavity of a mold, and the body 12 of the brake shoe cast therearound. The cast metal flows around, and completely fills, the interstices between the various strands 10 of the insert, resulting in the formation of a brake shoe body composed of cast iron, throughout which extend interlaced tubes or strands of hard wear-resisting steel, having a ductile metal core, the latter being 15 capable of reinforcing and tying together the shoe body.

What I claim is:—

1. A brake shoe insert consisting of a netting of connected and interlaced strands 20 of hard wear-resisting steel.

2. A brake shoe insert comprising a reinforcing member of openwork ductile metal, and a coating of hard steel carried by said reinforcing member.

25 3. A brake shoe insert comprising layers of openwork ductile metal, and a coating of hard steel surrounding the strands of said openwork metal.

20 4. A brake shoe insert comprising superposed layers of openwork ductile metal, and a coating of hard steel surrounding the strands of said openwork metal and tying and binding the layers thereof together.

5. A brake shoe insert comprising a bundle of openwork ductile metal, and a 35 coating of hard chilled steel upon the strands of said ductile metal.

6. A brake shoe comprising a cast metal body, and a netting of hard steel incorporated in said body. 40

7. A brake shoe comprising a cast metal body, a netting of hard steel, and a netting of ductile metal incorporated in said body.

8. A brake shoe comprising a cast metal body, a reinforcing member incorporated in 45 the body of said shoe and formed of openwork ductile metal, with a coating of hard steel thereon.

9. A brake shoe comprising a cast metal body, a reinforcing member therein formed 50 of a bundle of openwork ductile metal, and a coating of hard steel upon the strands of said openwork ductile metal.

10. A brake shoe comprising a cast metal body, an insert incorporated therein and 55 formed of a bundle of openwork ductile metal, and a coating of hard chilled steel carried by the bundle of openwork ductile metal.

Signed at Suffern, in the county of Rock- 60 land and State of New York, this 26th day of April, A. D. 1916.

HARRY JONES.
